UNITED STATES PATENT OFFICE.

HARRY H. HOOD, OF CHICAGO, ILLINOIS, ASSIGNOR TO ERNEST F. HERRMANN, OF CHICAGO, ILLINOIS.

GAS-ENGINE.

1,266,270.

Specification of Letters Patent. Patented May 14, 1918.

Application filed September 20, 1915. Serial No. 51,544.

To all whom it may concern:

Be it known that I, HARRY H. Hood, a citizen of the United States, residing at Chicago, in the county of Cook and State 5 of Illinois, have invented certain new and useful Improvements in Gas-Engines, of which the following is a specification.

My invention relates to improvements in gas engines, and refers more particularly to 10 improved means for cooling the interior of the cylinder or combustion chamber.

Among the salient objects of the invention are, to provide, in a gas engine, means for introducing a supply of cooling fluid into 15 the combustion chamber, whereby the heat of the exploded gases causing evaporation of said cooling fluid in the region where the latter is introduced; to provide a method of cooling of the type referred to in which the 20 cooling fluid may be introduced in varying amounts depending upon the conditions of load and speed under which the engine is operating; to provide a cooling system of the class described in which the admission of 25 cooling fluid may be properly regulated as to its time and rate of flow into the cylinder; to provide a system of cooling of the class described which may readily be utilized for engines operating upon either the four-cycle 30 or the two-cycle principle; to provide a cooling system of the class described in which the gasified cooling fluid forms a cooling envelop surrounding the heated exploded charge, and thereby prevent access of the 35 flaming gases to the parts which it is desired to cool; to provide a cooling system of the class described in which the heat subtracted by the cooling fluid from the parts to be cooled is expended in gasifying the 40 said cooling fluid, thereby producing an increase of propulsive effort in said cylinder; to provide a gas engine cooled internally and having its exterior insulated so as to prevent dissipation of heat energy outwardly to the 45 cylinder walls; to provide a gas engine cooled in the manner described, and in which the cooling medium may be applied to the parts to be cooled uniformly and in properly regulated amounts without the use of 50 complicated mechanism for distributing the fluid; to provide a gas engine of the class described in which the cooling medium operates in some measure as a lubricant for the cylinder, thereby effecting a marked econ- 55omy in the use of oil; to provide a gas engine

cooled as described, which, while being efficient, is at the same time simple and economical in construction and operation; and, in general, to provide an improved gas engine of the character referred to.

The accompanying drawings illustrate the application of my invention to a vertical gas engine having a single cylinder.

In said drawings—

Figure 1 is a section taken vertically 65 through the center of the engine, showing the piston in its lowermost position;

Fig. 2 is a fragmentary end elevation, looking from the rear of Fig. 1;

Fig. 3 is a section taken on the line 3—3 of 70 Fig. 1;

Fig. 4 is an enlarged view of the pump mechanism, shown in elevation; and

Fig. 5 is a section taken on the line 5—5 of Fig. 3.

Referring to the drawings, 10 represents the frame or crank casing of the engine in which is journaled the crank shaft 11, the latter being connected to the piston 12 by means of the connecting rod 13. The piston 12 reciprocates in the cylinder 14, the top of which is closed by the bolted-on head 15 in which are located the intake valve 16 and the exhaust valve 17. The latter may be of any usual construction designed to promote efficiency in the admission and emission of the charge, and may be operated by rocker arms 18 and 19 actuated by pusher-rods 20 and 21 in any approved manner, from the cam shaft 22. The piston is furnished with 80 the usual multiple piston rings 23, and, to the head of the piston is secured, by means of a central bolt 24, a bronze annulus 25 which preferably is insulated from the head of the piston by a mica disk 26. The head 15 of the 85 cylinder is lined with a substantial thickness of metal, such as bronze, having a high degree of heat conductivity, as shown at 27, said liner forming in conjunction with the annulus 25 the space in which the charge is 90 compressed prior to ignition. For a purpose which will hereinafter appear, the annulus 25 is constructed of substantially less diameter than the internal diameter of the liner 27. Said liner 27 is also insulated from the 95 head of the cylinder by means of an annular mica packing 28 and a mica disk 29.

In order to prevent escape of heat externally from the cylinder walls, I form on the exterior of the cylinder a pair of flanges 100

30 and 31 connected by a thin sheet iron jacket 32, the space between said jacket and the outside of the cylinder being filled with a heat insulator, such as asbestos, as shown at 33. Between the flange 30 and the upper flange 34, to which the cylinder head is bolted, I prefer to leave the cylinder wall exposed for convenient application of the water-conducting means which, as shown, 5 comprise a series of (in this case eight) small pipes 35, the inner ends of which are threaded into the cylinder wall, as shown at 36. Each of said pipes 35 is connected by means of a union 37 to a common pipe 38 10 encircling the cylinder, to which pipe is connected a riser 39 leading from the water pump, as shown in Fig. 2.

Describing the water pump details,—to the exterior of the crank casing is secured a 20 pump chamber 40 which is provided with the customary spring-controlled inlet and outlet valves, which are of any approved type and are not shown or specifically described. The piston 41 of the pump, which 25 is of the ram type, extends out of the stuffing box 42 and is slidably supported in a small lug 43 projecting from the pump housing, and is normally pulled outwardly from the pump chamber by means of a stiff coil 30 spring 44 which is interposed between the outer face of said lug 43 and a washer 45 secured on the projecting end of said ram. Intermediate the lug 43 and the stuffing box 42 is a pin 46 which forms a pivotal connection for the cam lever 47, the depending 35 end of the latter being provided with a cam roll 48 which is engaged by a cam 49 keyed to the projecting end of the cam shaft 22. The fulcrum of said cam lever 47 is a roller 40 50 engaging the side of said cam lever 47, said roller 50 being rotatably supported in a small bracket 51 which is slidably supported in the pump housing and is adjustable vertically by means of a screw 52 fitting 45 in a threaded hole in the base of said bracket 51. Said screw 52 is conveniently rotated by means of a hand-wheel 53 keyed to the lower end thereof. It is manifest that 50 movement of the bracket 51 in a vertical direction will change the position of the fulcrum for the cam lever 47, and the stroke of the pump will be correspondingly altered. This enables the supply of water to be very accurately regulated.

55 It will be observed that I absolutely dispense with extraneous means for cooling the cylinder of the engine. When starting the engine, I preferably shut off the supply of cooling water from the pump until the cylinder wall has attained a temperature high enough to rapidly vaporize any water injected into the cylinder for cooling purposes. The cam 49 is so synchronized with the other rotating parts that the cooling wa- 60 ter is preferably admitted when the piston

is at or near its innermost position when ignition takes place. In the four-cycle engine which I have illustrated, the injection of water is commenced slightly before the crank reaches the dead center and continues for a limited time, until the piston has descended slightly. By reference to Fig. 3, it will be observed that during the time the water is being injected, the ends of the injection pipes 36 are covered by the bronze annulus 25 70 25, but inasmuch as said part is made a substantial fraction of an inch less in diameter than the internal diameter of the cylinder, the water is admitted freely. The annular water space between the bronze annulus 25 80 85 and the liner 27 or wall of the cylinder is, however, made small enough so that the amount of water which is injected at any one time will more than fill said space and flow out of the annular cavity at the upper end 85 of said space. It is manifest that the effect of said annular space between the bronze annulus and the cylinder wall is equivalent to that of a swab or sponge which is charged with water and wipes down the interior of 90 the cylinder once every two revolutions.

The water, which, as just described, is forced out between the bronze annulus on the end of the piston and the wall of the cylinder when the piston is at or about its 95 topmost position, is distributed around the interior of the cylinder wall in a comparatively thin film or coating which almost instantaneously vaporizes, due to the fact that the temperature of the wall of the cylinder 100 is higher than that of boiling water, and in vaporizing forms a gaseous envelop which surrounds the exploded mixture and prevents access of the heated gases to the wall of the cylinder. The heat necessary to effect this vaporization of said film of water is obtained principally from the wall of the cylinder, and therefore does not materially reduce the temperature of the exploded gases occupying the interior of the cylinder 110 cavity. On account of the latent heat of evaporation of this film of water, a large supply of heat must of necessity be deducted from the cylinder walls in order to effect the gasifying of the said film, the abstraction of said heat lowering the temperature of the cylinder sufficiently for its practical operation.

115 It is apparent that the steam produced in the cylinder by evaporation of the film of cooling water admitted to its interior, becomes a part of the cylinder charge, and thus operates to increase the volume and pressure of the motive gases, resulting in a substantial increase in the efficiency of the 120 engine. The presence of the steam thus formed is also particularly efficacious in preventing fouling of the cylinder, due to deposits of carbon, or otherwise.

125 The presence of the film of water on the 130

cylinder wall above the piston rings is very helpful in maintaining a perfect gas-tight joint between the piston and the cylinder, in that it forms a water seal by virtue of which the escape of gas is largely prevented. It should be understood that while the gas of the cylinder is at maximum pressure, the water which is being admitted to the cylinder is ⁵ at the same or at a slightly greater pressure, and consequently positively prevents the escape of gas from the cylinder.

In my improved gas engine, the cooling fluid is conducted directly to the cylinder wall, which is the part desired to be cooled. It is a well known fact that when a film of water is applied to a metal surface and is there evaporated, a comparatively large proportion of the heat absorbed by the fluid when it is evaporated is abstracted from the metal surface, and a comparatively insignificant quantity of heat is taken from the surrounding gas or atmosphere into which the evaporated fluid is finally incorporated. This phenomenon is very pronounced where the liquid is evaporated very quickly from a surface having a high conductivity. Hence, in my engine, the heat which is necessary to effect the evaporation of the cooling fluid is taken principally from the cylinder wall, which is the part to be cooled; and to make such cooling still more effective, I use a high conductivity lining for the combustion chamber, as has been described.

The cooling effect of the liquid in its evaporation in the cylinder is thus expended mainly in reducing the temperature of the cylinder wall, and not in lowering the temperature and pressure of the exploded gases. It is my opinion, although I am not positive on this point, that the forming of an envelop of steam around the exploded charge is an important factor in preventing conduction or radiation of the heat between the highly heated gases and the cylinder wall. Said envelop of steam, as previously stated, is not produced by sacrificing the temperature or pressure of the exploded charge, but if anything, augments the volume and pressure of the charge.

In applying my invention to a single-cylinder four-stroke cycle gas engine having a stroke of fourteen inches and a diameter of eight inches, I preferably make the bronze cup or annulus approximately one one-hundred and fiftieth part of an inch less in diameter than the internal diameter of the cylinder, and I set the pump cam in such position that delivery of water is commenced approximately thirty degrees before the crank reaches the dead center at the ignition point of the cycle. The pump cam in the case cited is arranged to deliver water during a period corresponding to approximately one-sixth of a revolution of the crank

shaft. In order to make the pump operate in a positive manner and always deliver a definite amount of water to the cylinder at the proper time, I make the piping between the pump and the injection orifices as small as possible, consistent with the delivery of the required amount of cooling water. The injection orifices in the case cited are approximately one-thirty-second of an inch in diameter and eight in number, as shown, the piping between the pump and the common ring pipe supplying said orifices being one-eighth of an inch in diameter. This engine, when working at full load, uses about one pint of water per one hundred cycles, which corresponds to about one teaspoon full of water to each stroke of the pump. In the case cited, I have found that the most economical working temperature for the cylinder wall is approximately 155° Cent.

It will be obvious to those skilled in the art that my invention is capable of various modifications, and consequently I do not wish to be limited to the construction or manner of operation described, except as specified in the appended claims.

I claim—

1. In an internal combustion engine, the combination of a combustion chamber, and means for supplying a film of cooling water progressively to a portion of the area of the inner surface of said combustion chamber during the explosion stroke, whereby the wall of said combustion chamber is reduced in temperature.

2. In a gas engine, the combination of a cylinder provided with a bearing surface therein, a piston element adapted to reciprocate in said cylinder, and means for preventing escape of high pressure gases from said cylinder, including a pump for supplying water under pressure, means for actuating said pump during a period of high pressure, and means for conducting said water between the mutually sliding bearing surfaces of said piston and cylinder.

3. The process of deriving power from the explosion of gases, which consists in admitting an explosive mixture to the interior of a cylinder behind a piston, igniting the mixture and permitting the exploded gases to move the piston in the cylinder and in distributing a substantially continuous annular film of water over the interior surface of said cylinder behind said piston by the movement of said piston under the influence of said gases, gasifying said film of water principally by heat obtained from the wall of said cylinder whereby said wall is reduced in temperature, and exhausting said gases from the cylinder.

4. In a gas engine, the combination of a cylinder, a piston to reciprocate within said cylinder, said parts being provided with an

nular coacting bearing surfaces, one of said surfaces being adapted to be progressively exposed by the movement of the piston in the cylinder, and means for supplying water 5 under pressure between said bearing surfaces whereby the movement of the piston in the cylinder gradually exposes a water-carrying exposed surface in the interior of said cylinder during its reciprocatory outward movement.

5. In an internal combustion engine, the combination of a combustion chamber having a bearing surface therein, a part movable within said chamber to expose said bearing surface progressively during the expansion of the exploded charge, and means for progressively supplying by pressure a film of water to said exposed surface as it becomes exposed by the movement of said part, said 15 water emanating from the space between the coöperating bearing surfaces of said part and said chamber.

6. In an internal combustion engine, the combination of a combustion chamber having a bearing surface therein, a part movable within said chamber to expose said bearing surface progressively, said parts loosely fitting each other, and means synchronized with the crank shaft of the engine for delivering a supply of cooling fluid under pressure to the space between said parts whereby a film of fluid for cooling purposes is progressively distributed on said exposed bearing surfaces during a period of high 30 pressure within said combustion chamber, the delivery of fluid being suspended during a period of low pressure.

7. In an internally cooled internal combustion engine the combination of a cylinder, a piston adapted to reciprocate therein, one of said parts having a portion of its area adapted to be covered and uncovered by the relative movement of said parts, piston rings carried by said piston and arranged to prevent 45 the passage of the cylinder contents between said parts, and a pump synchronized with the movement of said piston for conducting a supply of liquid water under pressure to said area during the explosion stroke 50 of the engine, the supply of water being arrested during the period of admission of the explosive charge, whereby said water is vaporized by the heat of said parts which are reduced in temperature, the space between 55 said parts being completely occupied by water in liquid or gaseous form during the outward movement of said piston in the cylinder during the explosion stroke.

8. In an internal combustion engine, the combination of a cylinder, a piston adapted to reciprocate therein, one of said parts having a portion of its area adapted to be covered and uncovered by the relative slidable movement of said parts, the portion of the 65 piston having bearing with said area being

a comparatively loose sliding fit in said cylinder, and means for conducting a limited supply of water under pressure to the space intermediate said parts during a limited portion of the cycle of said engine.

9. In an internal combustion engine, the combination of a cylinder, a piston adapted to reciprocate therein, one of said parts having a portion of its area adapted to be covered and uncovered by the relative movement of said parts, the portion of the piston having bearing with said area being a comparatively loose fit in said cylinder, and means synchronized with the crank shaft of the engine for conducting a limited supply of water under pressure to the space between said parts during the explosion stroke of the engine, said supply being arrested during the period of admission of the explosive charge.

10. In an internal combustion engine, the combination of a cylinder, a piston adapted to reciprocate therein, one of said parts having a portion of its area adapted to be covered and uncovered by the relative movement of said parts, the portion of the piston having bearing with said area being a comparatively loose fit in said cylinder, means synchronized with the crank shaft of the engine for conducting a limited supply of water under pressure to the space between said parts during the explosion stroke of the engine, said supply being arrested during the period of admission of the explosive charge, and means for conducting heat from the non-bearing area of the cylinder to the water-cooled area.

11. In a gas engine, the combination of an internally cooled cylinder, a piston therefor having its inner end loosely fitting within said cylinder, piston rings for the outer end of said piston, a pump, means for actuating said pump during a period of high pressure, and a conduit for connecting said pump with the space between the piston end and the cylinder for conducting a limited supply of water into said space, the capacity of said space being of the order of the pump capacity.

12. In a gas engine, the combination of an internally cooled cylinder, a piston therefor having a cylindrical inner extension loosely slideable in said cylinder, piston rings for the outer end of said piston, a pump, a conduit connecting said pump with the annular crevice between said cylinder and said piston end, and means for actuating said pump during a period of high pressure within said cylinder whereby a supply of cooling water is forced out of said crevice and deposited upon the inner wall of said cylinder.

13. In a gas engine, the combination of a cylinder, a piston therefor having a cylindrical inner extension loosely slideable in said

- cylinder, piston rings for the outer end of said piston, a pump, a conduit connecting said pump with the annular crevice between said cylinder and said piston end, and means 5 for actuating said pump during a period of high pressure within said cylinder whereby a supply of cooling water is forced out of said crevice and deposited upon the inner wall of said cylinder, the capacity of said 10 crevice being less than the pump capacity.
14. In an internal combustion engine, the combination of a working cylinder provided at the outer end of the compression space with an outlet port, a piston provided with 15 an extension loosely slideable within said combustion space and adapted at its innermost position to cover said port, and a pump for injecting water through said port when covered by said extension.
15. In an internal combustion engine, the combination of a working cylinder provided at the outer end of the compression space with an inlet port, a piston provided with 20 an annular extension loosely slideable within said compression space and adapted at its innermost position to cover said port, piston rings so positioned that they never seal said port, a pump connected to said port, and means synchronized with the crank 25 shaft for actuating said pump to inject water into the annular crevice between said extension and the cylinder wall during a period of high pressure.
16. In an internal combustion engine, the combination of a working cylinder provided adjacent the outer end of the compression space with a circumferential series of inlet 30 ports, a piston provided with a cylindrical annular extension loosely slideable within 35 said cylinder and at its innermost position surrounding a substantial percentage of the total compression space, a pump connected to said port, and means for actuating said pump to force a supply of cooling water 40 through said port into the space between the extension and the cylinder wall during a period of high pressure.
17. In an internal combustion engine, the combination of a working cylinder provided 45 with a substantially cylindrical compression space, a piston having a cylindrical annular open ended extension slideable in said compression space and surrounding the same when in its innermost position, and a pump 50 for forcing water into the circumferential crevice between the extension and the wall of the combustion space of the cylinder.
18. In an internal combustion engine, the combination of a working cylinder provided with a substantially cylindrical compression space, a piston having a cylindrical annular open ended extension made of metal 55 of high heat conductivity slideable in said compression space and surrounding the same when in its innermost position, and a pump 60 for forcing water into the circumferential crevice between the extension and the wall of the combustion space of the cylinder.
19. In an internal combustion engine, the combination of a working cylinder provided with a substantially cylindrical compression space, a piston having a cylindrical annular open ended extension made of metal 65 of high heat conductivity slideable in said compression space and surrounding the same 70 when in its innermost position, and a pump for forcing water into the circumferential crevice between the extension and the wall of the combustion space of the cylinder, said combustion space being lined with 75 metal of comparatively high heat conductivity.
20. In an internal combustion engine, the combination of a working cylinder having a cylindrical combustion space lined with metal 80 of high heat conductivity, said cylinder being provided with a circumferential series of 85 restricted inlet ports located adjacent the outer end of the combustion space, a piston having an annular cylindrical open ended extension made of metal of high heat conductivity loosely slideable within the lining of 90 said compression space and adapted to cover said ports when the piston is in its innermost position, piston rings for said piston 95 always located below the inlet ports, a pump connected to said ports, and synchronizing means for actuating said pump during a period of high pressure and while the extension covers said ports, whereby a supply of 100 water is forced into the annular crevice between said extension and the cylinder wall.
